POLISHING IMPLEMENT

John Kaufmann, Astoria, N. Y., assignor to First
National Bank, Toledo, Ohio, as trustee

Application January 13, 1931. Serial No. 508,462

7 Claims. (Cl. 91—39)

This invention relates to floor waxing devices and in particular to a type in which the wax container may be replaced with a new one when the supply of wax in the old container is exhausted.

5 A particular object of my invention is to so support the container and covering therefor that the same may be quickly detached from the holder in which it is positioned and is so arranged that the wax content of the container 10 will be properly dispensed and the device may be employed for the even waxing of the floor and may be used with a minimum of effort and time.

A still further object of my invention is to provide in various forms, wax container holding 15 devices in which the essential elements of my invention are incorporated and which provide an assembly of holder and wax containing member that is cheap to produce and one which may be used with refills after the initial purchase of the 20 holding member.

Changes and variations may be made in the construction shown and described without departing from the principles of the invention or sacrificing its chief advantages; hence such invention is not to be confined to the structures 25 shown in the accompanying drawings;

Figure 1 is a view in elevation of a floor waxing device constructed in accordance with my invention.

30 Figure 2 is a bottom plan view of the floor waxing device illustrated in Figure 1 and showing the openings in the fabric covering surrounding the wax container.

Figure 3 is a section taken on the line 3—3 of Figure 1 and illustrates the relative location 35 of the parts.

Figure 4 is an enlarged section taken on the line 4—4 of Figure 2 and illustrates the method 40 of detachably securing the wax holding element and its fabric cover to the holding member.

Figure 5 is a view taken on the line 5—5 of Figure 4 and illustrates the retaining member in connection with which an end piece secured to 45 the waxing element is employed, whereby the waxing element is detachably secured to the holder.

Figure 6 is a view similar to Figure 5 illustrating a modified form of holder and one which, 50 due to its simplicity of construction, may be referred to as the preferred form of holding member.

Figure 7 is a bottom plan view of a tube which 55 may be employed in my holder and in which is retained the wax, the same being dispensed

through longitudinal slot-like openings in the bottom of the tube.

Figure 8 illustrates by a view in elevation, a modified form of my construction in which the waxing element is arranged to be slidably secured in a holding member.

Figure 9 is a section taken on the line 9—9 of Figure 8 and shows the relative location of the parts.

Figure 10 is a view in perspective of the under 65 side of a holder in connection with which is employed the waxing element.

Figure 11 is a view in side elevation of the waxing tube and its holding member.

Figure 12 is a top plan view of the wax holding 70 member illustrated in Figure 11, this figure showing the side cut-outs which are arranged to be engaged by the clips supported on the holder illustrated in Figure 10.

Figure 13 is a view similar to Figure 8 showing 75 a modified form of my invention in which cardboard backing is employed as a holder for the tube and is secured directly to a block member.

Figure 14 is a section taken on the line 14—14 of Figure 13.

In carrying out my invention, I employ as illustrated in Figures 1 to 6, a holder 5, consisting of a top piece 6 and a bottom block 7, or under piece, which is secured in any suitable manner to the top piece 6. To the top piece 6 there is secured in any suitable manner, the lower end 8 of a handle 9 through the medium of which the waxing device may be manipulated over a floor surface.

It is to be understood that in all of the forms of my invention, the handle 9 may be dispensed with, if desired, and the top piece 6 will then constitute a hand piece through the medium of which the device may be manipulated.

Attached to the under surface of the bottom block 7, I provide a spring steel plate 10 which is resilient, yet rigid enough to normally maintain a horizontal position when not supporting the wax container but when it has a wax container attached thereto, it will assume the position illustrated in Figure 1, the object being to make the wax container or polishing unit 11 bear evenly at all points on the surface to be polished and assist in extruding from the container all of the wax therein so that the waxing device may be for a maximum length of time without providing the same with a new polishing unit.

The ends of the spring plate 10 carry the retainers 12 which are secured thereto in any suitable manner as by rivets 13, for instance, and may 110

be made of any suitable material, being, as illustrated in Figure 5, provided with a central slot or opening 14 into which is received the tongue piece 15 carried at the end of the polishing unit 5. If desired, and if simplicity makes it a preferred form, I may employ the type of retainer illustrated in Figure 6 and indicated by the numeral 16 which is provided with an undergroove 17, which in cooperation with the top surface 10 of the plate 10, provides an opening or slot 17 in which is positioned, the tongue piece 15, one of which is carried at each end of the polishing unit 11.

The polishing unit consists of an inner malleable metallic tube 19 closed and bent at its opposite end as at 20 and surrounded by a flannel or other fabric cover 21, the ends of which are bent over as at 22 and secured by staples or otherwise to the tongue piece 15. Longitudinally of the bottom surface of the flannel 21, there is provided a series of openings 23. The metal tube 19 is pierced as at 24 when the polishing unit is in position for use so that the wax 25 in the tube may exude through the openings 24 and 23 to the surface to be polished.

As a modified form of my invention, the tube instead of being completely closed may, as illustrated in Figure 7, be provided with the longitudinal slots 26 which are in alignment with the openings 23. Another form of my invention, as illustrated in Figures 8 and 9 in which a backing 27 is provided into which is inserted a handle 28, the periphery of the backing 27 being encased in a heavy felt strip 29 which is secured to the backing in any suitable manner, such as by the tacks 30, this felt preventing marring of the furniture and walls when the polishing device is employed. The backing 27 is undercut to receive the slide 30 to which is secured, the heavy cardboard or thin wood or metal strip 31 which may be of single or double ply, the single ply being illustrated in Figure 8, while the double ply is illustrated in Figure 9 to provide the necessary resiliency so that the polishing unit is held flat on the floor, as illustrated in Figure 8, the unit in this instance being indicated by the numeral 32 and being constructed the same as heretofore described with the exception that the ends of the tube and the flannel covering 21 are secured as at 33 to the ends of the strip members 31.

In a further modified form of my invention illustrated in Figures 13 and 14, the intermediate slides 30 may be dispensed with and the strip portions 34 may be connected directly to the backing 35 in which is inserted a handle 36. It is to be understood that the fabric covering 21 of the polishing unit provided with the openings 23 longitudinally of the bottom surface thereof through which the wax may exude. It will be noted in connection with the form of my invention illustrated in Figures 8 and 9 that a clip 37 made of spring steel is employed to retain the slide 30 in position in the backing 27 and when it is desired to replace the unit or to use the same for hand operation, the spring 31 may be depressed in order to permit sliding thereover of the member 30.

A further modified form of my invention is illustrated in Figures 10, 11 and 12 in which a backing 37 is used having the side clips 38, one of which is provided with an adjusting screw 39 which is threaded into the block 37 and permits movement of the clip 38 toward and away from the opposite clip 38. In connection with this backing member 37, I employ a cardboard 40

having side cut-outs 41 into which fit the clips 38 to secure the cardboard or other strip member 40 in position against the backing 47. The usual polishing unit comprising the metallic tube and fabric covering, as indicated by the numeral 11 is employed in connection with strip member 40 and may be secured thereto through the medium of the staples 42 at the end and while it is not shown in this construction, any form of opening may be employed in the tube and in the fabric covering to carry out the purpose of my invention.

It is evident, therefore, that I have provided a simplified polishing member which permits of use directly by the hand or use after the manner of a mop in which the polishing unit is pushed along the floor through the medium of a suitable extended handle so that the person using the same does not have to get down on the floor on the knees. With the hand implement, furniture and flooring may be polished and I have made it possible to use a refill member consisting of a wax holding tube and cover therefor which may be thrown away when emptied and be replaced by another full tube, the openings in the bottom of the fabric cover acting as a guide to point out the locations of the places where the tube is to be pierced and the sealed metallic tube or container preserves the wax in proper shape until it is needed. The metallic leaf spring or strip member may be heavy enough to properly support the polishing unit and to maintain the same in shape so that even wear thereof is made possible as well as even distribution of the wax along the surface to be polished.

It is evident, also, that I have provided a polishing implement which is simple in construction, may be made at small cost and with a resultant saving to the consumer. Also the simplified construction of my device provides for the easy replacement of the polishing unit when the same has become empty and the whole structure provides a self-contained polishing implement which is easy to manipulate and supplies the wax as needed to the surface to be polished.

Because of a certain amount of flexibility in the strip 10, a limited amount of rocking movement of the presser head 7 against the cartridge 21 will be produced by the pushing of the implement back and forth and the frictional resistance developed between the pad 11 and the floor.

My invention is not to be restricted to the precise details of construction shown since various changes and modifications may be made therein without departing from the scope of the invention or sacrificing the advantages derived from its use.

What I claim is:—

1. A polishing device comprising a supporting member, a flexible strip having edge cut-outs therein, clips on said supporting member for engaging the strip in said cut-out portions, and a polishing unit secured to said strip.

2. A polishing device comprising a flexible member, sockets secured to the ends of said flexible member, and a polishing device the ends of which are provided with fingers insertible into said sockets when the flexible member is flexed.

3. In a device for spreading plastic surfacing material, a collapsible container of liquid impervious flexible substance in which a body of said material is enclosed, a fabric envelope extending around said container and including an apertured region lying against a longitudinal face of said container and forming a working face for engaging a surface to be treated, a presser head from which said envelope and container are sus-

- pended, arranged to apply pressure to that side of the container which is opposite said working face, and a handle on which said presser head is carried, whereby said container may be applied 5 to the surface under treatment through the medium of only said envelope, with its aforesaid longitudinal face lying parallel and close to said surface, and will extrude its contained material under pressure developed by back and forth movement applied to it through the medium of said handle.
4. In a device for spreading plastic surfacing material, a collapsible container of liquid impervious flexible substance in which a body of 15 said material is enclosed, a fabric envelope extending around said container and including an apertured region lying against a longitudinal face of said container and forming a working face for engaging a surface to be treated, a presser head 20 from which said envelope and container are suspended, arranged to apply pressure to that side of the container which is opposite said working face, and a handle on which said presser head is carried, said container being mounted so that 25 back and forth movement transmitted to it from said handle will, in conjunction with resistance developed by the frictional contact of said working face with the surface under treatment, result in a certain amount of rocking movement of said 30 container relative to said presser head.
5. In a device for spreading plastic surfacing material, a collapsible container of liquid impervious flexible substance in which a body of said material is contained, a distributor member extending around said container and including an 35 apertured region lying against a longitudinal face of said container and provided with a working face for engaging a surface to be treated, a presser head from which said distributor member is suspended, arranged to apply pressure to that side 40 of the container which is opposite said working face, said container being suspended in said distributor, and a handle on which said presser head is carried, whereby said container may be applied 45 to the surface under treatment through the medium of only said distributor, with its aforesaid longitudinal face lying parallel and close to said surface, and will extrude its contained material 50 under pressure developed by back and forth movement applied to it through the medium of said handle.
6. In a device for spreading plastic surfacing material, a collapsible container of liquid impervious flexible substance in which a body of said material is contained, a distributor member extending around said container and including an apertured region lying against a longitudinal face of said container and provided with a working face for engaging a surface to be treated, a presser head from which said distributor member is suspended, arranged to apply pressure to that side of the container which is opposite said working face, said container being suspended in said distributor, and a handle on which said presser head is carried, said container being mounted so that back and forth movement transmitted to it from said handle will, in conjunction with resistance developed by the frictional contact of said working face with the surface under treatment, result in a certain amount of rocking movement of said container relative to said presser head.
7. In a device for spreading plastic surfacing material, a collapsible container of liquid impervious flexible substance in which a body of said material is enclosed, a distributor member extending around said container and including an apertured region lying against a longitudinal face of said container and forming a working face for 100 engaging a surface to be treated, a presser head in engagement with that side of the container which is opposite said working face, arranged to apply pressure thereto, and a member from which said presser head is suspended adapted to be 105 grasped by the hand of the operator, whereby said container may be applied to the surface under treatment through the medium of only said distributor, with its aforesaid longitudinal face lying parallel and close to said surface, said member being connected to said presser head in such manner that back and forth movement of the device over a surface, applied to it through the medium of said member will cause said container to extrude its contained material through said 110 apertured region.
